[57] CLAIM

The ornamental design for a wall mounted power control, as shown and described.

DESCRIPTION

FIG. 1 is a front elevational view of a wall box mounted power control showing our new design with the front cover in its open position.

FIG. 2 is a right-hand elevational view thereof.

FIG. 3 is a left-hand elevational view thereof.

FIG. 4 is a top plan view thereof.

FIG. 5 is a bottom plan view thereof.

FIG. 6 is a rear elevational view thereof. The portions of the drawing disclosure shown in broken lines are for illustration only and form no part of the claimed design.

FIG. 5.
